UNITED STATES PATENT OFFICE.

A. L. WHIPPLE, OF ELMIRA, NEW YORK.

MACHINE FOR TRIMMING WALL-PAPER.

Specification of Letters Patent No. 25,696, dated October 4, 1859.

To all whom it may concern:

Be it known that I, A. L. WHIPPLE, of Elmira, in the county of Chemung and State of New York, have invented a new and Improved Machine for Trimming Paper-Hangings; and I do hereby declare that the following is a full and exact description thereof, reference being had to the accompanying drawings, making part of this specification, 5 in which—

Figure 1, is a plan view; Fig. 2, is a side elevation; Fig. 3, is an end elevation; Fig. 4, a sectional view of the spool-block and portion of the bed, B.

Similar letters refer to corresponding parts in all the figures.

As represented in the drawings, A is the frame of the machine, which supports, by the standards b b, the spindle, E, for rolling 20 up the paper as it is trimmed. On the opposite side, a bed, B, is attached to the frame by means of the bolt c passing through a slot, which admits of the bed sliding endwise to a certain extent. This bed has a grooved 25 way upon its upper side, in which is fitted the movable spool-block, G, which is provided with the spring, d, to hold it firmly on whatever part of the bed it is placed, and yet allow it to be moved the length of the 30 ways to adapt it to the length of the roll.

At one end of bed B, the spool-head D, is pivoted to the standard e which is permanently attached to the bed; while the opposite spool-head C, has a spindle, f, which 35 passes through the block, G, in which it revolves, and is provided with a coiled spring i which throws it outward from the block, but yields when endwise pressure is exerted against the head. The roll of paper to be 40 trimmed is placed in this spool, the block G, being run on the bed far enough to receive it on the pivots g g, where it is crowded up till the coiled spring presses it firmly against the fixed head D.

Intermediate between the spool and the reeling spindle E, a lever, F, is pivoted at one end of the frame. On the fulcrum end of this standards arise, which form bearings for the shafts which carry the rotary knives 45 or shears, a a, by which the paper is cut. These may be circular knives as represented, with their axes diverging to bring the edges in closer contact at the cutting point, or any other variety of cutters adapted to the purpose. A bar of wood, H, elevated above the 50 lever to the point of contact of the knives, forms a friction break for the paper as it is

drawn over it, keeping it smooth and steady, while the opposite end serves as a handle by which the lever is moved to regulate the 60 direction of the cutting.

A hand crank is attached to the upper knife spindle by which motion is given, and it is conveyed to the lower knife, and to the reeling spindle, by means of pulleys and 65 bands, or by gearing.

The operation is as follows: A roll of paper is placed between the spool-heads C, D, and the bed, B, adjusted to bring the edge to be trimmed on a line with the cutters, 70 when the end is passed over the brake H, between the knives and caught upon the spindle E, as it is revolved by means of the crank h. The spindle rolls the paper around itself, as it unwinds it from the spool, the 75 pressure of the head C, preventing it from unwinding too fast, and the cutters remove the edge in the meanwhile. The operator turns the crank with his right hand, while with his left he holds the end of the lever 80 and bar H, moving it back and forth as is required to make the knives follow the edge of the pattern, which is seldom or never perfectly straight.

The paper being drawn through straight, 85 and the cutters being attached to the lever F, the slightest movement of the latter changes the direction in which they cut, and the operator can with perfect ease follow the edge of the figure so as to insure its 90 matching its adjunct however untrue it may be. When a roll is trimmed it is removed by raising the end of the spindle from its bearing and slipping it off.

These improvements render the machine 95 perfectly practical, and enable it to do the work well and expeditiously with slight labor and attention from the operator.

I do not claim the use of cutters whose shafts are placed at different angles, such 100 being a well known device; but

What I claim as my invention, and desire to secure by Letters Patent, is—

The manner of constructing the spool, with fixed rotating head D, and yielding 105 head, C, in combination with the movable bed B, for holding the roll firmly in the proper relative position to the knives, substantially as herein described.

A. L. WHIPPLE.
